DANIEL V. WATERS, OF OAK PARK, ILLINOIS, ASSIGNOR TO WESTERN ELECTRIC COMPANY, INCORPORATED, OF NEW YORK, N. Y., A CORPORATION OF NEW YORK

DRIVING DEVICE

Application filed March 17, 1930. Serial No. 436,340.

This invention relates to driving devices and more particularly to driving devices for wire drawing machines.

An object of the invention is to provide a simple and efficient driving device, and one which will contribute to the provision of an efficient and durable mechanism for handling strand material at high speeds.

One embodiment of the invention contemplates the provision, in a wire drawing machine, of a flexible driving device wherein a cylindrical ball bearing gear member, driven by external teeth thereon, is provided with internal teeth loosely fitting into peripheral teeth of a shaft extending through the cylinder at an angle to the axis thereof. Both the cylindrical gear member and the shaft are rotatably journaled in the frame of a wire drawing machine, and are actuated by a drive gear which meshes with the external teeth of the cylindrical member.

The invention will be more fully understood by reference to the following detailed description read in conjunction with the accompanying drawing, forming a part thereof, in which

Fig. 1 is a schematic elevation of a wire drawing machine constituting one embodiment of the invention; and

Fig. 2 is an enlarged fragmentary plan section of the driving device and associated apparatus.

Referring to the drawing, in which similar parts have been designated by identical reference numerals, a wire drawing mechanism, generally denoted by the numeral 10, is mounted upon a base 11 and enclosed by a casing 12, consisting of opposing side walls 13-13 and a rear wall 14 (Fig. 2) rigidly secured to the side walls and base of the casing. Within the casing and spaced from the rear wall 14, but secured to the side walls of the casing so as to be parallel with the rear wall, is a support 15. An idler shaft 17 is secured in the rear wall 14 and the support 15 and extends perpendicularly therefrom to support a plurality of individually rotatable idler sheaves 19, 19, of which 5 are shown in the present embodiment. A motor 21, of any suitable type, is provided with a drive shaft

22, which also extends perpendicularly with respect to the rear wall and support, being suitably journaled in an enlarged portion 23 of the support in such manner as to insure its being firmly held and rotatable therein in 55 a substantially frictionless manner. A drive gear 25 is keyed to the shaft 22 and disposed thereon approximately midway between the rear wall 14 and the support 15. A die box 26 of any suitable type is rigidly mounted 60 upon the face of the support 15 and extends therefrom substantially perpendicular to the plane of the support, and provides means for holding a plurality of forming dies 27, 27 in position with respect to a wire 29 which is 65 drawn therefrom. In the embodiment shown, five of such dies are used. The wire 29 is drawn from the dies 27 by means of a stepped capstan 30, the latter being keyed upon a capstan shaft 31 so as to be rotated thereby. The 70 rear wall 14 and support 15 are suitably apertured to accommodate fixed, oppositely disposed mounting plates 33 and 34, respectively, which are each provided with an annular flange 35, the flanges extending toward each 75 other from their respective plates to provide a support for a cylindrical member or hollow gear 37. The mounting plates 33 and 34 are provided with suitable ball bearings 41, 41 by means of which the gear 37 is maintained 80 between the flanges 35, 35 and its substantially frictionless rotation is permitted.

The hollow gear 37 is provided with a relatively wide axial aperture 42 extending longitudinally thereof upon the lining or internal surface of which teeth 43, 43 are formed. The capstan shaft 31 extends through the longitudinal aperture of the cylindrical member and is provided with a plurality of external teeth 45 which loosely but continually 85 mesh with the internal teeth 43 of the cylindrical member. The mounting plate 34 is provided with a centrally disposed aperture 46, and the mounting plate 33 is provided with an aperture 47 disposed appreciably 90 away from the center point for accommodating the rotatable capstan shaft therein diagonally of the axis of the gear 37. The mounting plates 33 and 34 are respectively provided with suitable ball bearings 49, and roll- 100

er bearings 50 for facilitating the rotation of the shaft 31. The cylindrical gear 37 is provided with a plurality of peripherally disposed teeth 51 with which the drive gear 25 meshes.

From the foregoing it may be observed that when it is desired to rotate the capstan 30 and the idler sheaves 19 about diagonally extending axes, as for instance, to cause the 10 wire 29 to shift across the surfaces of the steps of the capstan in order to prevent deleterious grooving and frictional wear therein, the arrangement described may be advantageously employed. The wire 29 is introduced in the chamber from the right, (Fig. 1) passes under the initial or innermost idler sheave 19 through the innermost die 27, which is that die having the largest bore of all the dies 27, and thence to the capstan 30, about the lowest step of which the wire is looped. The wire is then brought over and under the second idler sheave 19, through the second die 27 having the next largest bore, and thence is looped around the 25 second step of the capstan 30. This process is continued until the wire is drawn over each of the idlers, through each of the dies 27 in the order of their graduated bore diameters, and about each of the graduated steps of the 30 capstan 30. As is common in most wire drawing machines, the idler sheaves serve to guide the wire to the dies and the capstans serve to pull the wire through the dies, the latter being held stationary against the pull 35 of the wire 29 by the die holder 26.

The capstan shaft 31, since it is firmly mounted in the diagonally disposed apertures 46 and 47, may not be driven from the drive shaft 22 because there is no commercially feasible method of producing suitable gears in a shaft inclined with respect to the drive shaft as is the capstan shaft 31, for cooperation with the driving gears. However, this difficulty is overcome by causing the capstan 45 shaft 31 to extend through the cylindrical member 37, and since the latter is rotatably secured between the flanges 35, 35 and is provided with the central aperture 42, the diameter of which is sufficient to allow clearance between the member 37 and the shaft 21, the driving of the capstan 30 is secured without slippage or loss of power. It will also be observed that the internal teeth of the member 37 and the external teeth of the shaft 50 31 mesh loosely, having a clearance sufficient to permit enough flexibility for changing the angle of the shaft in a considerable degree. Both the drive gear 25 and the external teeth of the hollow gear 37 constitute straight 55 gears which permit the rotation of the hollow gear 37 in accordance with the rotation of the drive shaft 22.

This combination of a hollow driven member, through which is passed a subordinate driving member such as the capstan shaft

31 may likewise be found in a system where the hollow member is driven from the drive shaft by suitable gearing or belting, and the subordinate member driven by leather, fabric or any type of flexible coupling other than the gears 43 and 45. The embodiment specifically described above has however, been found to provide a dependable and efficient arrangement for driving the inclined shaft from the main shaft and seems to be the 70 most effective form of connection.

Although the invention has been described above in connection with a high speed wire drawing machine, it will be apparent that the invention is capable of numerous modifications and should not, therefore, be limited other than by the appended claims.

What is claimed is:

1. In a driving device, a casing, a pair of supporting members removably supported thereby and defining a chamber therebetween, a cylindrical member having hub portions at the ends thereof and rotatably supported in the supporting members upon the hubs and extending into the chamber in the housing, a plurality of internal teeth carried by the cylindrical member, a shaft journaled in the supporting members and extending through the cylindrical member diagonally to the axis thereof, a plurality of peripheral teeth carried by the shaft and meshing with the internal teeth of the cylindrical member, and means engageable with the cylindrical member between the supporting members for rotating the cylindrical member to drive 100 the shaft.

2. In a driving device, a casing, a driving shaft supported in the casing, a driving member carried by the driving shaft, spaced mounting plates removably supported in the 105 casing, a cylindrical member having teeth internally thereof and hub portions at the ends thereof and rotatably supported by and between the mounting plates, a shaft journaled in the mounting plates and extending through the cylindrical member diagonally of the axis thereof and having external peripheral teeth in engagement with the teeth of the rotatable member, and means for establishing driving connection between the 110 driving member and the rotatable member.

In witness whereof, I hereunto subscribe my name this fifth day of March A. D., 1930.

DANIEL V. WATERS.
